HOLSTER

Byron Engle, Kansas City, Mo.

Application March 29, 1945, Serial No. 585,423

4 Claims. (Cl. 224—3)

1

This invention relates to holsters and particularly articles of manufacture having the ability to support small arms in the nature of pistols.

The primary object of this invention is to provide a holster for pistols or the like, that is capable of swinging from one position to another as it is being worn—all to the end that the wearer may experience greater comfort, greater accessibility to the weapon, and the possibility of releasably maintaining that portion of the holster against swinging movement when such condition is desired.

Other objects of the invention include the provision of a holster for pistols or the like, which is comprised of two primary sections, one of the same being a belt-engaging support and a hollow body having parts for releasably latching the same together, and means for pivotally mounting the hollow body upon the aforesaid support.

Other aims of the invention include a large number of specific details of construction, all of which contribute to the beneficial results arising from the employment of pistol holsters made as illustrated in the accompanying drawing, wherein:

Fig. 1 is a perspective view of a holster made to embody the present invention.

Fig. 2 is another perspective view of the holster illustrating the swingable body thereof in a position different from that illustrated in Fig. 1.

Fig. 3 is a back elevational view of the holster.

Fig. 4 is an enlarged fragmentary detailed sectional view taken on line IV—IV of Fig. 3; and

Fig. 5 is a similar sectional view taken on line V—V of Fig. 3 and looking in the direction of the arrows.

Holsters of the character chosen to illustrate the invention, are customarily used by officers of the law, members of the armed forces, and those habitually carrying side arms as required in their line of duty.

The use of such side arms, and therefore in holsters to support the same, has accompanying inconveniences because of the rigid type of holsters heretofore employed. For example, when patrolmen ride scout cars or spend the major portion of their time in an automobile, a rigid holster will force the supporting belt upwardly and out of adjustment to a point where the pistol carried by the holster will not be readily available upon leaving the motor car.

The problem just set forth is but one example of the reason why the body portion of the holster, about to be described, must be swingably secured to a support.

2

In the drawing, the numeral 10 designates a hollow body having an open top and comprised of an outer wall 12, an inner wall 14, and a retaining strap 16. As clearly illustrated in Figs. 1 and 2, inner wall 14 is cut to present an extended portion 18, whereon is supported one section of the parts for releasably holding body 10 in a set position with respect to belt-engaging support 20.

Support 20 is a looped member, preferably formed of leather, to present the tubular portion 22 through which passes the belt of the wearer. Glove fasteners of conventional type and designated by the numeral 24, secure together the overlapped marginal edges of the material from which tubular portion 22 is formed.

In constructing the support 20, three distinct pieces of leather are used. The strip 26 is relatively short; strip 28 is long enough to be rebent to overlie the upper marginal edge of strip 26; and the filler member 30 lies between the lowermost portions of strips 26 and 28. Suitable stitching 32 is employed to produce a unitary member of support 20.

When fasteners 24 are in the operative position, the belt may be slid through loop 22 or said loop may be opened and the belt sipped thereinto by moving the thus freed ends of strips 26 and 28 around the belt before snaps 24 are again brought into securement.

Hollow body 10 is formed of leather and stitched to insure rigidity as shown in Figs. 1, 2 and 3. The extended portion 18 of body 10 should be provided with a curved upper edge 34 to avoid corners or other elements that may hinder manipulation.

Body 10 and support 20 are pivotally interconnected, as clearly illustrated by Fig. 4. Rivet 36 having head 38 is embedded between strip 28 and filler 30. The shank of rivet 36 extends through one layer of body 10. In this respect, it will be noted that body 10 is formed of leather and that the projected portion 18 has two thicknesses of sheet material 40 between which washer 42 and the upset portion 44 of rivet 36 is caused to lie. The pivotal interconnection between body 10 and support 20, is, therefore, rivet 36, and body 10 moves about the axis of this rivet when the latching mechanism about to be described, is inoperative.

In the embodiment illustrated, the latching mechanism for holding the body 10 against movement relative to support 20, comprises a pair of heavy glove fasteners, one section 46 whereof 55 is carried by body 10 while the cooperating sec-

tion 48 is mounted on support 20. Section 46 includes the rounded heads which do not mar the surface of the leather when the glove fasteners are inoperative and as body 10 is swung about the axis of rivet 36. Rivet 36 and the sections 46 and 48 of the two glove fasteners are far enough apart to permit flexing the material from which projected portion 18 is made to allow disengagement of sections 46 and 48 when such becomes necessary. The sections of the glove fasteners are so placed as to be movable into engaged operative condition when hollow body 10 assumes the position illustrated in Fig. 1. The longitudinal axis of body 10 is at an angle to the perpendicular and the lower end of this said body is projected downwardly and rearwardly from support 20 when the holster assembly is worn in the normal position.

When the holster is carried by the officer into an automobile, sections 46 and 48 are parted and body 10 may swing around pivotal point 36 to a place where the belt and support 20 will remain in a normal condition as body 10 swings to a point more nearly horizontal than that assumed when the snap fasteners are operative.

The angle of inclination illustrated in Fig. 1, is desirable because a quick withdrawal of the pistol is possible without interference and as soon as retaining strap 16 is unsnapped. If the wearer is desirous of having the body 10 swing to position, such as shown in Fig. 2, where the pistol will be beside the thigh and resting upon the seat of the automobile, the body may be caused to assume the position shown in Fig. 2.

Actual practice has demonstrated the benefits arising from a holster made as above described and practically all of the problems heretofore encountered when wearing a holster of prevailing type, have been solved. Ease of operation, automatic adjustability to desired positions with respect to the body, and other benefits of the structure will be apparent to those skilled in the art.

Obviously, holsters of the type shown and specified, may be made to present physical characteristics different from those illustrated, and therefore, it is desired to be limited only by the scope of the appended claims.

Having thus described the invention, what is claimed as new and desired to be secured by Letters Patent is:

1. A holster for pistols or the like comprising

a hollow, open top body having an outer wall and an inner wall, having a portion extending beyond one end of the outer wall; a belt-engaging support for the body in overlapping relation with the said extended portion of the inner wall; means for pivotally interconnecting the support and said extended portion of the inner wall; and parts on the support and on the inner wall respectively, for holding the body against movement about the pivotal means, said parts being manually secured in the holding position upon pressing together the inner wall and the support when the body is disposed in a certain position with respect to the support.

2. A holster for pistols or the like comprising a hollow, open top body having an outer wall and an inner wall, having a portion extending beyond one end of the outer wall; a belt-engaging support for the body in overlapping relation with the said extended portion of the inner wall; means for pivotally interconnecting the support and said extended portion of the inner wall; and parts on the support and on the inner wall respectively for holding the body against movement about the pivotal means, said parts being manually secured in the holding position when pressing together the inner wall and the support when the body is extended downwardly and rearwardly with respect to the support when the latter is hanging at the side of the wearer.

3. A holster for pistols or the like comprising a hollow, open top body having an inner and an outer wall; a belt-engaging support in overlapping relation with the inner wall of the body; means for pivotally interconnecting the support and said inner wall; and parts for latching together the support and the inner wall, said parts including at least one snap fastener having a section on the support and a mating section on the body.

4. A holster for pistols or the like comprising a hollow, open top body having an inner and an outer wall; a belt-engaging support in overlapping relation with the inner wall of the body; means for pivotally interconnecting the support and said inner wall; and parts for latching together the support and the inner wall, said parts including at least one snap fastener having a section on the support and a mating section on the body, said sections being in place to mate when the body is disposed at an angle to the perpendicular.
